UNITED STATES PATENT OFFICE.

GEORGE J. THOMAS, OF LANSING, MICHIGAN, ASSIGNOR TO DUPLEX TRUCK COMPANY,
OF LANSING, MICHIGAN.

RADIATOR.

1,887,415.

Specification of Letters Patent. Patented Apr. 20, 1920.

Application filed June 27, 1917. Serial No. 177,249.

To all whom it may concern:

Be it known that I, GEORGE J. THOMAS, a citizen of the United States, residing at Lansing, county of Ingham, State of Michigan, have invented certain new and useful Improvements in Radiators, of which the following is a specification.

This invention relates to improvements in radiators.

10 The objects of this invention are:

First, to provide a radiator comprising a plurality of detachable sections that may be quickly and easily detached from the upper and lower water tanks.

15 Second, to provide a structure of the class described, in which each of the detachable sections is so formed as to provide a structure which can successfully withstand the jolts and jars to which it is subjected without causing it to leak.

20 Further objects, and objects relating to structural details, will definitely appear from the detailed description to follow.

I accomplish the objects of my invention 25 by the devices and means described in the following specification. The invention is clearly defined and pointed out in the claims.

30 A structure which is a preferred embodiment of my invention is clearly illustrated in the accompanying drawing, forming a part of this specification, in which:

Figure I is a detail front elevation of a radiator embodying my invention.

Fig. II is an enlarged detail section taken 35 on a line corresponding to line 2—2 of Fig. I, showing details of the construction of the filling opening and the closure therefor.

Fig. III is an enlarged detail section taken 40 on a line corresponding to line 3—3 of Fig. I, showing the means for securing the radiator section manifolds to the water tank.

Fig. IV is a plan view of one of the radiator section manifolds.

Fig. V is a front elevation thereof.

45 In the drawing similar reference characters refer to similar parts throughout the several views, and the sectional views are taken looking in the direction of the little arrows at the ends of the section lines.

50 Referring to the drawing, the reference characters 1 and 2 indicate the upper and lower water tanks respectively, of my radiator, which are held in proper relation by means of suitable side standards 3. The

upper side of the upper water tank 1 is 55 formed with a central well or recess 4, the bottom of which is provided with a threaded aperture 5 for the threaded lower end of the closure cap 6. As shown in Fig. II, the cap 6 is cylindrical in form, and hollow, and 60 is provided with apertures 7 in the walls thereof which open into the well 4.

A shoulder 8 coacts with the bottom of the depression to limit the inward movement of the cap 6. When the cap 6 is removed the 65 water for filling the radiator may be poured directly into the depression 4, and it is, therefore, unnecessary to provide a funnel for this purpose. In the event of the radiator "boiling over" the water is collected in 70 the well 4 and returned to the radiator through the vents 7.

The water tanks 1 and 2 are provided with opposed inwardly extending channels 9 and 10, respectively, having the vertical 75 walls 11 and 12, respectively, which are provided with a plurality of spaced openings 13.

The detachable radiator sections each comprises an upper header 14 and a lower 80 header 15. These upper and lower headers are identical in construction and each comprises a pair of manifolds 16 having open ends 17 adapted to be received in the shoulderered openings 13. Shoulders 18 adjacent 85 the open ends 17 coöperate with the shoulders of the openings 13, suitable gaskets 19 being provided for these joints.

The two manifolds 16 are made integral by the spaced webs 20 and 21 and the inner 90 sides of the manifolds are provided with a plurality of spaced apertured threaded bosses 22, which receive the ends of the radiator tubes 23. The ends of these tubes are secured in the bosses 22 and the joints 95 made watertight by means of suitable glands 24 and gaskets 25, the ends of the tubes entering the bosses being straight and smooth.

If desired, the radiator tubes 23 may be 100 provided with the usual radiating disks 26. To secure the radiator sections in position, I provide clamping members 27 having rounded conformed projections 28 at each end thereof, one of which bears against the front wall of the adjacent water tank and the other of which is received in the concaved depressions 29 formed in the ends of

the headers. The clamps 27 are adjustably secured to the wall of the tank by means of screws 30.

By forming each radiator section with headers comprising integrally united manifolds, each manifold and its connected radiator tubes forms a stiffening element for the other connected radiator element, thereby providing a radiator section of such rigidity 10 that jars and jolts and other strains are not likely to open the tube joints. Furthermore, by forming adjacent pairs of manifolds into an integral structure, a single clamp may be used for clamping a pair of the manifolds to 15 the radiator tanks, thereby producing a more economical structure to manufacture, and one which can be assembled and disassembled much more quickly than those structures in which each of the manifolds is 20 separately formed.

My improved radiator is especially designed by me for use on trucks, tractors and the like, which are subjected to heavy work and in which there is considerable liability 25 of injury to the tubes.

With the parts arranged as I have illustrated and described, the sections are all freely accessible for renewal or repair, and in case of removal of a section the manifold 30 openings in the tanks may be plugged and the radiator used until a new or repaired section can be inserted.

I have not attempted to illustrate or describe certain modifications which might be 35 desirable to adapt my improvements to radiators of different forms or types, as I believe the disclosure made will enable those skilled in the art to which my invention relates to embody or adapt the same as may be desired.

Having thus described my invention, what 40 I claim as new and desire to secure by Letters Patent, is:

1. In a radiator, the combination of an upper tank having a downwardly offset 45 channel on its under side and a lower tank

having an upwardly offset channel on its upper side, said channels being disposed at the rear of the tanks and having spaced shouldered manifold openings in their front walls, a plurality of radiator sections each 50 comprising upper and lower headers, each header consisting of a pair of integral manifolds having shouldered open inner ends disposed in the manifold openings of said tanks and a plurality of laterally projecting opposed apertured bosses, radiator tubes disposed with their ends in said apertured bosses of said headers, packing glands provided with gaskets threaded upon said bosses whereby said tubes are retained and supported, gaskets for said manifold openings, and clamps mounted on an overhanging portion of said tanks engaging the outer ends 55 of said manifolds.

2. In a radiator, the combination of an upper tank having a downwardly offset channel on its under side and a lower tank having an upwardly offset channel on its upper side, said channels being disposed at the rear of the tanks and having manifold 60 openings in their front walls, a plurality of radiator sections each comprising upper and lower headers, each header consisting of a pair of integral manifolds having shouldered open inner ends disposed in the manifold 65 openings of said tanks and a plurality of laterally projecting opposed apertured bosses, radiator tubes disposed with their ends in said apertured bosses of said headers, and packing glands provided with gaskets threaded upon said bosses whereby said tubes are retained and supported.

In witness whereof I have hereunto set my hand and seal in the presence of two witnesses.

GEORGE J. THOMAS. [L. S.]
